JOINING STRIP FOR METAL SHINGLES

Charles F. Sperry, Burbank, Calif., assignor to
Alumalux Company, Pasadena, Calif., a corpora-
tion of Nevada

Application August 11, 1947, Serial No. 767,906

4 Claims. (Cl. 108—13)

1

This invention relates to a joining strip for metal shingles and has been primarily designed for use in connection with the metal shingles disclosed in my co-pending application, Serial No. 731,966, filed March 3, 1947.

A primary object of the invention is to provide a joining strip that may be advantageously used to effect a joint or connection between the adjacent edges of two adjoining metal shingles so as to effectively prevent leakage therebetween and which when regarded from the top of the roof will present a neat and attractive appearance.

In my co-pending application above referred to there is disclosed a roof which presents a Bermuda type appearance consisting of rafters on which sheathing boards are secured. These sheathing boards are so arranged as to be stepped; that is, their lower edges are slightly spaced from the rafters or other supporting structure. The top surface of each sheathing board slopes upwardly from its lower edge to a point adjacent the lower edge of the sheathing board next above where the lower edge of the next above sheathing board is disposed upwardly and of full thickness. Over these sheathing boards there are positioned metal shingles each shingle being of suitable length and covering its respective sheathing board from top to bottom thereof. Each shingle adjacent its upper edge is reversely bent providing a downwardly opened pocket and terminating in an upstanding flange constituting a securing flange that can be nailed into the lower edge of the sheathing board next above. The reversely bent portion that provides the pocket is inserted between the underside of the sheathing board adjacent its lower edge and the rafter or supporting structure. The lower edge of each shingle is bent downwardly so as to cover over the securing flange of the shingle next below and has a returned portion which is designed to enter the downwardly opened pocket of the shingle next below. The improved joining strip is so designed as to be suitable for use in conjunction with shingles of this connection to effectively provide a joint between the adjacent edges of adjacent shingles and which will not mar or detract from the overall appearance of the roof.

Another object of the invention is to provide a joining strip that may be easily and economically manufactured and which can be easily assembled with metal shingles of this character.

With the foregoing and other objects in view, which will be made manifest in the following

2

detailed description and specifically pointed out in the appended claims, reference is had to the accompanying drawings for an illustrative embodiment of the invention, wherein:

- 5 Fig. 1 is an isometric view of a joining strip embodying the present invention;
Fig. 2 is a partial view perspective illustrating a roof of the type disclosed in my co-pending application and illustrating the joining strip embodying the present invention as having been incorporated in the roof construction;
10 Fig. 3 is a sectional view taken substantially upon the line 3—3 upon Fig. 2;
Fig. 4 is a transverse sectional view through the joining strip and through the adjoining shingles and may be regarded as taken substantially upon the line 4—4 upon Fig. 3; and
15 Fig. 5 is a partial view in vertical section taken substantially upon the line 5—5 upon Fig. 4.
20 Referring to the accompanying drawings wherein similar reference characters designate similar parts throughout, the roof as disclosed in my co-pending application consists of rafters or other supporting structure indicated at 10 on which sheathing boards 11, 12 and 13, for example, are positioned in slightly overlapping and stepped relation. These sheathing boards may either be supported on tapered blocks 14 that are mounted on the rafters 10 or the sheathing boards may themselves be cut so as to be tapered and assume a position wherein their upper edges are disposed beneath the lower edges of the sheathing boards next above and in slight spaced relationship thereto so that there are small recesses 15 beneath the lower edges of the sheathing boards. Each metal shingle or roofing strip is of suitable length one of which is indicated at 16. This shingle adjacent its upper edge is reversely bent as at 17 providing a downwardly open pocket indicated at 18 and the reversely bent portion is then bent upwardly at right angles to form a securing flange 19 that is adapted to be fastened to the bottom edge of the sheathing board next above such as by nails 20. Each shingle near its lower edge is bent downwardly as indicated at 21 forming a covering flange that may cover the heads of the nails 20 on the shingle next below and is then returned as indicated at 22 providing a flange portion that enters the pocket 18 of the shingle next below.

25 The above described construction in general conforms to the disclosure made in my co-pending application. However, instead of merely overlapping the side edges of the shingles where

they adjoin one another I provide a joining strip. This strip as illustrated in Fig. 1 consists of a lower or main section of sheet metal indicated at 23 which near its upper edge is reversely bent as at 24 providing a downwardly open pocket 25. The reversely bent portion is then bent upwardly at right angles as indicated at 26 in a manner to provide a securing flange corresponding to the securing flange 19. Near the bottom edge the strip or section 23 is bent downwardly as indicated at 27 to be positioned over the bottom edge of the sheathing board to which it is applied. Near the center of the section 23 the section is embossed upwardly forming on the underside of the section a curve 28 and on the upper side a bead or rib 29. This bead or rib extends from the reverse bend 24 downwardly to the flange 27 and may continue downwardly over the face of the flange 27. A suitable waterproof or water resistant mastic indicated at 30 (see Fig. 5) is then applied to the rib or bead 29 and a relatively narrow strip of sheet metal 31 is applied to the section 23 so as to straddle the rib or bead. This second section of sheet metal has its upper end extending into the pocket 25 and is spot welded as indicated at 32 at intervals along the length of the section 31. In performing the spot welding operation the spot welds 32 are formed between the section 31 and the bead 29 directly through the mastic 30 thus rigidly and permanently securing the section 31 centrally to the section 23 intermediate the side edges of the section 23. Those portions of the section 31 which extend laterally from the line of spot welds are slightly spaced from the section 23 a distance sufficient to accommodate the adjacent edges 33 and 34 of adjoining shingles or roofing sections 35 and 36. The lower end of the section 31 extends beyond the point at which the flange 27 is bent downwardly as indicated at 37 and carries a returned portion 38 capable of entering the pocket 18 of the shingle or roofing section next below. When initially supplied the downwardly bent portion 37 extends downwardly at an angle to the flange 27 so as to be in spaced relation thereto.

As illustrated on the drawing, the roofing sections or shingles are preferably slightly corrugated to break the uniformity in appearance of the sheet metal although this is not essential. Where the shingles or roofing sections are thus slightly corrugated the sections 23 and 31 are similarly corrugated as illustrated. The use of such corrugations, however, is not essential. In applying the shingles or roofing sections to the stepped sheathing boards and using the joining strip a shingle such as the shingle 16 or 36 is positioned on the sheathing board with its reversely bent portions 17 extending into the pocket 15. The nails or fasteners 20 can then be driven into the securing flange 19 and into the sheathing board 11 as illustrated on the drawing. At the side edge of the section 36 the joining strip embodying the present invention is applied and in so doing it is merely necessary to position the flange 26 against the sheathing board 13 and slide it laterally with relation to the secured shingle 36. In so doing that portion of the lower section 23 is slipped beneath the edge 34 of the shingle 36 and the edge 34 is then caused to enter the space between the section 31 and the section 23. When the joining strip is thus positioned it may be secured in position on the

sheathing board 11 by driving fasteners through the securing flange 26 into the sheathing board 13 next above. The roofing section or shingle 35 may then have its edge 33 slid on the lower section 23 so as to enter the space between the section 23 and the upper section 31 and may be secured in position by driving nails 20 through its securing flange 19. When the various shingles and joining strips are thus assembled together on the roof the portions 37 may be bent downwardly so as to overlie the spaces between the flanges 21 and the returned portions 38 are caused to enter their respective pockets 18 beneath the returned portions 22 on the shingles. In this manner it will be appreciated that the improved joining strip when used will not only effectively prevent leakage between the side edges of adjoining shingles or roofing sections but will present a neat and attractive appearance in that on the upper side of the roof there is merely exposed the upper surfaces of the relatively narrow sections 31 which overlie the beads between the edges 33 and 34. The securing flanges 19 on the roofing sections overlie the securing flanges 26 of the joining strips and although there will be slight spaces therebetween approximately equal to the space between the edges 33 and 34 these spaces will be covered by the covering flanges 21 of the shingles next above. In constructing a roof of this character, it is usually desirable to have the joints between the edges 33 and 34 of adjoining shingles in any one tier or on any one sheathing board disposed in staggered relation to the joints between the shingles or adjacent sheathing boards.

In the above described construction it will be appreciated that an improved joining strip is provided which may be easily and economically manufactured and which may be assembled together with shingles or roofing sections to effectively perfect the joint between the side edges of adjoining shingles.

Various changes may be made in the details of construction without departing from the spirit and scope of the invention as defined by the appended claims.

I claim:

1. A joining strip for metal shingles comprising a section of sheet metal having its lower edge bent downwardly and which adjacent its upper edge is bent reversely to provide a downwardly open pocket and then upwardly to provide a securing flange and a second section of sheet metal secured centrally to said section having laterally extending portions beneath which the adjacent edges of adjoining shingles may be positioned the lower end of said second section extending beyond the downwardly bent lower edge of the first section and bent downwardly and then returned at right angles to the downwardly bent portion so as to extend into the pocket of a subjacent shingle, said second section having its upper end extending into the reverse bend of said first section.

2. A joining strip for metal shingles comprising a first section of sheet metal which adjacent its upper edge is reversely bent and the reversely bent portion being then bent upwardly to provide a securing flange, said section adjacent its lower edge being bent downwardly, there being a longitudinally extending bead formed on said section, mastic on the bead, a second section of sheet metal having its upper end extending into the reverse bend of the first section and having its lower end projecting beyond the downwardly bent portion at the lower end of the first section and then

returned at right angles, said second section being positioned so as to straddle the bead and being spot welded to the first section through the mastic.

3. A joining strip for metal shingles comprising a first section of sheet metal which adjacent its upper edge is reversely bent to provide a downwardly open pocket, and a second section of sheet metal secured to said first section intermediate the side edges of the first section and having laterally extending portions beneath which the adjacent edges of adjoining shingles may be positioned and having its upper end extending into the reverse bend of said first section.

4. A joining strip for metal shingles comprising a first section of sheet metal which adjacent its upper edge is reversely bent to provide a downwardly open pocket and having its lower edge bent downwardly, and a second section of sheet metal secured to said first section intermediate the side edges of the first section and having laterally extending portions beneath which the adjacent edges of adjoining shingles may be positioned

and having its upper end extending into the reverse bend of the first section and having its lower end bent downwardly.
